UNITED STATES PATENT OFFICE.

MARTIN MEYER, OF OMAHA, NEBRASKA.

COMBINATION DOORWAY AND STEP CLOSURE FOR STREET-CARS.

1,075,049.

Specification of Letters Patent.

Patented Oct. 7, 1913.

Application filed April 11, 1912. Serial No. 690,009.

To all whom it may concern:

Be it known that I, MARTIN MEYER, a citizen of the United States, residing at Omaha, in the county of Douglas and State 5 of Nebraska, have invented certain new and useful Improvements in Combination Doorway and Step Closures for Street-Cars, of which the following is a specification.

This invention relates to a combined door-10 way and step-closure for street cars, particularly adapted for use in connection with pay-as-you-enter cars, and has for its ob-ject to provide means for the coincident closure of the double passageway or door-15 way and folding of the door-step, the two closures to be effected by a single act or movement of a person in charge of the car.

The invention includes an upright, elongated barrier-frame or gate disposed exte-20 riорly of the car and adapted to be swung downwardly or upwardly for obstructing or clearing the passageways, the pivotally or hingably mounted step moving simultaneously to an upright or horizontal position, 25 devices being employed and operating automatically to cause these parts to become locked or secured at the time the step is folded.

The invention also has reference to the 30 use of an adjustable counterbalance which not only tends to equalize the weight of the gate and connected parts to cause convenient operation, but automatically sustains the gate in its uppermost position when the 35 step is lowered, and by reason of its momentum causes effective engagement of the gate with the detent-members for locking the gate when it is lowered, and swinging the step to a vertical or "closed" position.

40 The invention also includes automatically operative means for preventing the outward swinging movement of the gate at the passenger platform or doorway after the gate has been lowered, this outward movement 45 generally being caused by pressure delivered from within, or pressure occasioned by an overcrowded condition of the car.

While the principal object is the provision 50 of simple, practical and effective means to effect the simultaneous movements of a gate and step, to open or close a passageway of a car, convenient means are incidentally provided and found of advantage for connect-

ing or disconnecting certain parts, so that the gate may be operated, whenever desired, 55 in conjunction with or independently of the step.

The invention also discloses means, which operate automatically to secure or "lock" the pivotally mounted step in a vertical or 60 "closed" position, and automatic means for releasing the step from its "locked" or vertical position, so that it may be swung downward to a horizontal position.

With the foregoing objects in view, and 65 others as hereinafter outlined, the invention presents a novel construction, combination and arrangement of parts as described and claimed, and as illustrated in the drawing, 70 wherein—

Figures 1 and 2 are side elevations, showing the rear part of a car; Fig. 1 showing relative position of parts when the gate has been lowered and the step has been swung upward to a vertical position, Fig. 2 showing 75 relative position of parts when the gate has been elevated and the step lowered to a horizontal position. Figs. 3 and 4 are rear end views of a car, portions of the car frame being broken away and in section 80 to clearly illustrate the mounting of certain parts. Figs. 5 to 15, inclusive, are enlarged, detail views to clearly show construction of certain parts appearing in Figs. 1, 2, 3 and 4. Fig. 5 is a side view of the vertical 85 actuating-rod. Fig. 6 is a vertical, side view of a hook or detent-member, a contact-block or buffer also being shown. Figs. 7 and 8 are detail views relating to Fig. 9 to show the pivotal mounting of the reversible 90 display plate in one of the ends of the gate. Fig. 9 is a broken side view of the gate or barrier-frame. Fig. 10 is a side view of parts, showing a crank-connection between a sprocket wheel and the upper terminal of 95 the actuating-rod, a part of the housing-case also being shown. Fig. 11 is a side view, partly broken, of the housing or case for the sprocket wheels and chain. Fig. 12 is an end view of the step, when swung to an 100 upright position; said view illustrates the mounting of the step, and shows the lower part of the actuating-rod; also, in section, it shows a part of the car frame. Fig. 13 is a view of the hand lever and illustrates its 105 mounting upon a sprocket wheel, the casing

and chain being in section. Fig. 14 is an end view of the step when swung to a horizontal position. Fig. 15 illustrates the mounting of the lower terminal of the actuating-rod upon the car-step.

Referring to the drawing for a more particular description, numeral 1 indicates the platform of a car having a doorway or passageway 2. It will be understood that by the term doorway used in this connection, is meant the entrance or exit way generally provided in the side of the car, and below the doorway, mounted upon hinge-members 3 and 4, arranged in pairs, is indicated the doorstep 5. Each of the hinge-members 3, best shown in Fig. 14, preferably consists of a straight strap, and hinge-members 4 are preferably angular in form; members 3 may be mounted upon 10 and may extend below the frame-member 6 of the car, their lower terminals providing a support for shaft 7 upon which the hinge-members 4, at the junction of their right-angled arms, may be mounted. 15 The step 5 is secured upon one arm of each angular hinge-member 4, and upon the other arms of these hinge-members is mounted the guard or riser 8 and contact-bar 9, said bar being disposed upon the rear part and 20 adjacent to the ends of said arms. Contact-bar 9 is disposed parallel with shaft 7 and has a length greater than the riser, so that its ends will bear upon the rear part of hinge-members 3 when the car step moves 25 to a horizontal position, these bearings being for the purpose of sustaining the step, and for resisting a downward pressure thereon. The contact-bar is preferably constructed of metal and it may operate as an 30 element to equalize the weight of the riser as compared with the weight of step 5, so that the swinging movements of the step may be facilitated.

While I have described, in detail a preferred mounting for the car step, I do not limit myself in this respect, and it may be provided with any suitable mounting below the doorway of a car so that it may be swung transversely in an arc, substantially 40 of 90 degrees.

At 10, above step 5, is indicated a gate or barrier-frame preferably of flat rectangular form. It is disposed exteriorly of the car; it may have any suitable width, and preferably has a length somewhat greater than the width of the doorway 2. At 11, upon the car, are indicated brackets providing bearings for shaft 12, said shaft having at one of its ends an angular arm 13 provided with a weight 14. This weight is provided with a set-screw so that it may be adjusted longitudinally of arm 13, and the opposite end of the shaft is provided with a crank 15.

At 16, transversely-disposed and rigidly 50 mounted upon shaft 12, are indicated lift-

ing-arms; and hingably mounted at 17 upon arms 16 are the supporting-arms 18, said arms 18 being disposed transversely with reference to and rigidly mounted upon the upper part of the gate frame. If provision is made for rotating this shaft 180 degrees, 70 arms 16 may be swung transversely of the car, and the gate may be disposed as a barrier in its lowermost position, shown in Figs. 1 and 4, or may be swung upwardly 75 to the positions shown in Figs. 2 and 3. To cause a reciprocatory rotary motion of the shaft for these purposes, the same to be under convenient control of an operator, any suitable means may be provided, the means 80 herein shown being the sprocket wheels 19 and 20, carrying the sprocket chain 21 (Fig. 11). A housing or casing 22 is preferably employed to extend transversely of the car, and it may be suitably secured to the car frame as shown in detail in Fig. 13. Wheel 20 may be provided with a hand-lever 23. Wheel 19 preferably is disposed in a terminal of the casing opposite to wheel 20, and is rigidly mounted upon shaft 12; and shaft 85 25 may have bearings in said casing. The housing or casing is preferably rectangular in cross-section, and it may be of angular form to occupy a limited space below the roof of the car.

At 24 is indicated a link or actuating-rod, said rod being shown in broken lines in Figs. 1, 2, 3 and 4, and best illustrated in detail in Figs. 5, 10 and 12. It is provided at its terminals with transverse heads or 90 projections 25 extending in one direction, and slots 26 are formed in these projections.

Upon the lower side of step 5, between its edges and adjacent to one of its ends, is mounted a bracket 27 (Figs. 1, 2, 15), and mounted in this bracket is a pin 28 adapted to engage within the slot of the lower projection of the actuating-rod, and the mounting of the pin 28 within this slot may be maintained by means of the keeper 29. The upper terminal of the actuating-rod is mounted upon crank 15 of shaft 12, crank pin 15' engaging within the slot 26 of the projection 25 of this upper terminal.

From the description it will be seen that 115 rod 24 may have longitudinal reciprocation; the movement of the rod in one direction under control of the hand-lever will cause the gate to swing downward, and coincidently therewith the step will swing from a horizontal to a vertical position; and at this time the crank-pin 15' and pin 28 may slide within slots 26. Also, by operating the hand-lever, rod 24 may have a movement in an opposite direction to cause the gate to 120 swing upward, and coincidently with this movement of the gate the step will swing downward from a vertical to a horizontal position.

In practice, the actuating-rod is disposed 130

within the wall or partition of the car, and it is desirable that it may move in a vertical plane; the provision of the transverse projections or heads 25 and slots 26 permit this movement, the crank-pin 15' and wrist-pin 28 moving freely within these slots.

In operation, the hand-lever may be swung in one direction with the result that the gate will swing downward to obstruct the passageway. At 30 mounted upon the car are provided hooks or detent-members, and upon the ends of the gate are indicated projections, contact-members or pins 31 adapted to be engaged by the hooks when the gate completes its downward movement. The hooks are supported upon springs 32 so that pins 31 will automatically engage the hooks, and the gate will therefore be detained in its lowermost position and will resist outward pressure. This feature is considered to be of advantage since the gate will be held in a manner to prevent accidental injuries occasioned by an overcrowded condition of the car. When the gate is swung upwardly the pins pass outward from their engagement with the hooks.

At 33 and 34 are indicated cushions or buffer-blocks mounted upon the car, these being for contact, respectively, with the gate and with arms 16, to prevent undue vibration from their contact with the car, when they have approximately completed one of their swinging movements.

In order that the gate may be of limited weight, it is constructed as a tubular, rectangular frame as shown in the drawings; and within the area or space between the sides and ends of the frame may be mounted a reversible display-sign 35. The construction, in detail, of the parts employed for mounting the sign within the frame in a manner to be invertible, is shown in Figs. 7, 8 and 9, and requires no particular description, except to state that the sign may be moved longitudinally within the frame against the force of spring 36 for manually inverting the sign; and after it has been inverted or disposed in a vertical plane it will be normally sustained in that position, since the broad portion *x* of one of its supporting-pins (Fig. 8) will have a bearing in the elongated aperture *y* of the adjacent end of the gate.

At 37 is indicated a controlling-rod pivotally mounted at one of its ends at 38 upon and near the upper side of the gate, its opposite end being pivotally mounted at 39 upon the car, adjacent to the doorway; and the rod tends to maintain the gate in a vertical position during its swinging movements. The actuating rod 24, near its lower end is provided with a knuckle joint 40 (Fig. 15), this being for the purpose of conveniently disconnecting said rod from the wrist pin 28, so that the step may remain

stationary while the gate is operated, for in some instances it is desired that the gate may be swung independently of the step.

While the parts would probably be operative without the employment of the weighted arm 13, it operates to advantage as a counter-balance, so that lever 23 may be more easily moved when lifting the gate. Also by reference to Fig. 4 it will be seen that when the step 5 has been moved to a vertical position, arm 13 at that time has been swung far enough to dispose weight 14 "past center", or outwardly of the bearings of shaft 12, and therefore said weight tends to detain the shaft and step in a stationary position after the step has completed its upward swinging movement.

By referring to Fig. 3 it will be seen that when the gate has been elevated, the weighted arm has not, at that time, been swung far enough to be disposed in alinement with lifting-arms 16, and therefore the weight 14, after the shaft has completed one of its movements, tends to sustain the gate in a stationary, elevated position.

While I have shown and described shaft 12 as having bearings in brackets 11 (Fig. 1), and having a length sufficient to extend between these brackets, it will be understood that the parts would be operative and the lifting-arms 16 could have swinging movements transversely of the car in an arc of substantially 180 degrees by actuation of wheel 19 and the sprocket chain, if that portion of the shaft between arms 16 was removed, and therefore I do not wish to limit myself to the use of shaft 12 as shown, although it is the preferred construction.

Having fully described my invention, what I claim and desire to secure by Letters Patent is—

1. In combination, a vehicle provided with a doorway, a pivotally mounted step below the doorway, a gate disposed adjacent to the doorway and mounted exteriorly of the car; an actuating-rod connected with the gate and step, said rod being longitudinally-movable to cause coincident swinging movements of the step and gate, alternately, in directions toward and opposed to each other, and a controlling-rod connected with the gate and car for maintaining the gate in a vertical position during its swinging movements.

2. The combination in a passenger car having a doorway, a pivotally mounted step below the doorway, a pair of lifting-arms mounted above the doorway and adapted to have swinging movements transversely of the car, a gate hingably supported by the lifting-arms, and means connecting the lifting-arms with the step so that during one of their movements the gate will move upwardly, the step having a downward swinging movement.

3. In combination, a vehicle provided with a doorway, a pivotally mounted step below the doorway; a horizontal shaft mounted above the doorway, said shaft being provided with transversely-disposed lifting-arms and adapted to have a reciprocatory rotary movement; a gate provided with supporting-arms having their terminals hingably mounted upon the terminals 10 of said lifting-arms, and means connecting the shaft with the step so that a movement of said shaft in one direction will cause the gate and step to move toward each other.
4. In combination, a car having a doorway, a pivotally mounted step below the doorway; a horizontal shaft adapted to have a reciprocatory rotary movement and provided with a pair of transversely-disposed lifting-arms and a weighted arm; a gate 15 supported by said lifting-arms; devices connecting the shaft with the step so that a movement of the shaft in one direction will cause the gate to move upwardly, the step having a downward swinging movement, the weighted arm of the shaft tending to sustain the gate and step stationary after they have been moved.
5. The combination in a passenger car having a doorway, a pivotally mounted step below the doorway, lifting-arms mounted 20 above the doorway and adapted to have swinging movements transversely of the car in an arc of substantially 180 degrees, a gate hingably supported by the lifting-arms, and means connecting the lifting-arms with the step so that during one of their movements the gate will move downwardly, the step having an upward swinging movement.
6. In combination, a vehicle provided 25 with a doorway, a pivotally mounted step below the doorway; a horizontal shaft mounted above the doorway, said shaft being provided with a pair of lifting-arms and adapted to have a reciprocatory rotary movement; a gate having a pair of supporting-arms hingably mounted upon said lifting-arms, and means connecting the shaft with the step so that a movement of the shaft in one direction will cause the gate to move upwardly, the step having a downward swinging movement.
7. In combination, a car having a doorway, a pivotally mounted step below the doorway; a horizontal shaft adapted to have 30 a reciprocatory rotary movement and provided with a pair of transversely-disposed lifting-arms and a weighted arm; a gate hingably supported by said lifting-arms; devices connecting the shaft with the step so that a movement of the shaft in one direction will cause the gate to move upwardly, the step having a downward swinging movement; means connected with the gate and car for maintaining the gate in substantially 35 a vertical position during the movement of
- said gate, the weighted arm of the shaft tending to sustain the gate and step stationary after they have been moved.
8. The combination in a car having a doorway, a pivotally mounted step below the doorway, lifting-arms mounted above the doorway and adapted to have swinging movements transversely of the car in an arc of substantially 180 degrees, a gate hingably supported by the lifting-arms, means connecting the lifting-arms with the step so that during one of their movements the gate will move downwardly, the step having an upward swinging movement, and means connected with the gate and car for maintaining the gate in substantially 40 a vertical position.
9. In combination, a vehicle having a doorway, a pivotally mounted step below the doorway; a horizontal shaft adapted to have a reciprocatory rotary movement, said shaft being provided with a crank and transverse lifting-arms; a gate hingably supported by the lifting-arms, and a link 45 pivotally connecting the crank with the step, the operation being that the movements of the shaft will cause the gate and step to have simultaneous swinging movements in directions opposed to each other.
10. In combination, a car having a doorway, a step pivotally mounted upon the car, a horizontal shaft provided with a crank and mounted in suitable bearings above the doorway; a link pivotally connected with said crank and step; a gate provided with 50 contact-members and supported by the shaft, said shaft being rotatable to cause an upward swinging movement of the step and a downward swinging movement of the gate, the contact-members of said gate moving into engagement with said detent-members.
11. The combination in a passenger car having a doorway, a pivotally mounted step below the doorway, a pair of lifting-arms mounted above the doorway and adapted to have swinging movements transversely of the car, a gate hingably supported by the lifting-arms, means connecting the lifting-arms with the step so that during one of 55 their movements the gate will have an upward swinging movement, the step swinging downward, and a rigid controlling-rod pivotally connected with the gate and car for maintaining said gate in a vertical position during its swinging movement.
12. In combination, a vehicle provided with a doorway, a pivotally mounted step below the doorway; a horizontal shaft mounted above the doorway, said shaft being provided with transversely-disposed lifting-arms and adapted to have a reciprocatory rotary movement; a gate provided with supporting-arms having their terminals hingably mounted upon the ter- 60

minals of said lifting-arms; means connecting the shaft with the step so that a movement of said shaft in one direction will cause the gate and step to move toward each other, and a rigid controlling-rod pivotally connected with the gate and car for maintaining the gate in a vertical position during its movement.

13. In combination, a car having a doorway, a pivotally mounted step below the doorway; a horizontal shaft having a weighted arm and adapted to have a reciprocatory rotary movement, said shaft being provided with a pair of transversely-disposed lifting-arms; a gate hingably supported by said lifting arms; an actuating-rod pivotally connecting said crank with the step, and a controlling-rod pivotally mounted on the car and engaging said gate.

14. In combination, a car having a doorway and a pivotally mounted step, said step being provided with a wrist-pin; a horizontal shaft provided with a crank-pin and transverse lifting-arms, said shaft being mounted in suitable bearings above the doorway exteriorly of the car and adapted to have a reciprocatory rotary movement; a gate carried by said lifting-arms; and a link formed with transverse terminal heads with slots formed therein, said link being disposed between the step and said shaft with the slots of its transverse heads traversed by said crank-pin and wrist-pin.

15. In combination, a vehicle having a doorway, a detent member and a pivotally mounted step, said step being provided with a wrist-pin; a horizontal shaft adapted to have a reciprocatory rotary movement and

provided with a crank-pin and with transverse lifting-arms, a gate carried by said lifting-arms and provided with a contact-member; a link formed with transverse, terminal heads with slots formed therein, said link being disposed between the step and said shaft with the slots of its transverse heads traversed by said crank-pin and wrist-pin, the contact-member of said gate being adapted to make engagement with the detent member of the car at the time the shaft has completed one of its movements.

16. In combination, a vehicle provided with a detent-member, a doorway and a pivotally mounted step below the doorway; a horizontal shaft mounted above the doorway, said shaft being provided with a crank and a pair of lifting-arms; a gate provided with a contact-member and having a pair of supporting-arms hingably mounted upon said lifting-arms; an actuating-rod pivotally connected with said crank and step, said shaft being movable to cause simultaneous swinging movements of the gate and step in directions opposed to each other, said contact-member at the termination of the movement of the gate in one direction making engagement with said detent-member; and a rigid controlling-rod pivotally mounted upon the gate and engaging the car for maintaining said gate in a vertical position during its movements.

In testimony whereof I have affixed my signature in presence of two witnesses.

MARTIN MEYER.
